UNITED STATES PATENT OFFICE.

WILLIAM A. MATHESON, OF CHICAGO, ILLINOIS, ASSIGNOR TO ROLL-A-WAY BED CORPORATION, OF CHICAGO, ILLINOIS, A CORPORATION OF ILLINOIS.

HINGE.

Application filed May 11, 1923. Serial No. 638,179.

My invention belongs to that general class of devices known as hinges, and relates particularly to a device for connecting cooperating parts together, whereby the same have 5 a desired relative pivotal movement. The device has particularly as an object a hinged construction especially adapted for use on beds or the like, which may be folded or closed so as to reduce the size of the same 10 when not in use, but the device, however, may be employed wherever found applicable.

The invention has among its objects the production of a device of the kind described that is simple, convenient, durable, reliable, 15 efficient and satisfactory for use wherever found applicable. It has particularly as an object the production of a hinged construction of the kind described which will not only serve to rigidly secure parts of the bed 20 together but will also pivotally or adjustably secure the legs thereto. The preferred construction is also adapted to limit the movement of the legs when they are moved to operative or folded positions.

25 Many other objects and advantages of the construction herein shown and described will be obvious to those skilled in the art from the disclosures herein given.

To this end my invention consists in the 30 novel construction, arrangement and combination of parts herein shown and described, and more particularly pointed out in the claims.

In the drawings, wherein like reference 35 characters indicate like or corresponding parts:

Fig. 1 is a sectional view illustrating my improved hinge as applied to a bed construction.

40 Fig. 2 is a sectional view taken substantially on line 2—2 of Fig. 1.

Fig. 3 is a sectional view taken substantially on line 3—3 of Fig. 1, and

45 Fig. 4 is a sectional view taken substantially on line 4—4 of Fig. 1, the hinge and leg moved to folded positions.

Referring to the drawings, my preferred type of hinge consists of two cooperating members, 1 and 4, which are suitably secured 50 together and arranged for attachment to the parts to be hinged or connected together. The member 1 comprises a plate provided with flanges 2, which flanges are extended and bent over at one end as at 3 so as to overlap

one another or to be brought adjacent. I 55 have illustrated the same as overlapping.

The member 4 consists of a plate provided with side flanges 5 which are extended and bent over as indicated at 6—6. The members are so proportioned that one may be 60 inserted in between the flanges of the other. In the particular instance illustrated, member 4 is so proportioned that the flanges 5 will lie between and closely fit the flanges 2. The hinge parts or members are secured together by a rivet or bolt 7 or equivalent means, a spacer 8 being preferably employed 65 as shown.

As before mentioned, my improved hinge is particularly adapted for bed constructions, 70 and I have therefore shown the same as applied to a bed for securing several parts together, but in view of the fact that the preferred type of bed forms no part of the present invention, I have not considered it necessary to illustrate the complete bed herein. 75 My device is adapted for use on any type of bed where folding legs are employed.

In the construction which I have shown, 80 9 represents one of the side frame bars or rails, which is of angle iron construction, and including the flange 10, the bar being secured to hinge part 1 by rivets 11 or their equivalents. Secured to the part 4 is a leg 13, this 85 being secured in place by a rivet or bolt 14 or equivalent means for the purpose. There is also shown a bed frame or rail portion post 12, which is secured to the portions 3 by a bolt 15. It will be noted that the portions 3 as shown are formed with a slot 16 so that the post 12 may be secured in place so that it abuts and closely fits the end of the leg portion 13 and substantially forms a continuation thereof. The flanges 3 and plate 4 are arranged to conform to or fit the portions 90 12 or 13, their particular design depending 95 upon the design of parts 12 and 13 which in the present instance are shown as cylindrical. Obviously, they may be any other desired design.

It will be noted that when the bed is open or in operative position as shown in Fig. 1, with the post portions 12 and 13 in registry, the end of plate 4 and the flanges 6 will abut the lower edge of the flanges 3, thereby limiting the movement of the leg and positively preventing further opening. This relieves any strain on the bolt 15 as the weight of the 100 105

bed is carried on the leg 13, being transmitted through the hinge parts rather than through the portion 12 alone. It will be noted that when the leg is folded as indicated in the dotted lines in Fig. 1, or in full lines in Fig. 4, one of the flanges 5 will abut on the flange 10 of the rail as indicated at 17, thereby limiting the closing movement of the leg and maintaining the same in the desired relation with the rail or bar 9. The parts may be so designed that the movement of the leg may be as preferred. The present construction is adapted not only to pivotally secure the leg 13 to the bar, but also the frame or post portion 12 to the bar or frame of the bed, and likewise maintain parts 12 and 13 in the desired relation.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a bed construction, a post comprising a pair of sections arranged end to end, a rail, and a hinge comprising a pair of members, one of which connects said rail to one of said post sections and the other of which is secured to the first-mentioned hinge part and to the other post section, said hinge members adapted to abut against one another when the post sections are arranged end to end, and one of said hinged members abutting against said rail when said post sections are swung substantially perpendicular to each other.

2. In combination, a pair of post sections adapted to be vertically arranged end to end, a hinge member comprising two parts pivotally interconnected, one of said parts secured to one of said sections and the other of said parts secured to the other of said sections, and a rail carried by one of said hinge parts and adapted to be brought into engagement with the other of said hinge parts to form a stop therefor to limit its pivotal movement when said post sections are arranged substantially perpendicular.

3. In combination, a pair of post sections adapted to be arranged end to end, a hinge member comprising a pair of parts, one of which is connected to one of said posts and the other connected to the other of said posts, said last-mentioned part adapted to carry a rail member, and said hinge parts being pivotally interconnected, one of said parts constructed to lie within the other and having an end wall adapted to be flush with the adjacent end wall of the other part when said hinged parts are swung to their limit of movement in one direction.

4. In combination, a pair of adjacent post

sections adapted to be arranged end to end, a hinge member comprising a pair of parts adapted to be pivotally interconnected and each having a wall adapted to register with and abut against one another when the hinge parts are moved to their limit of pivotal movement in one direction, one of said hinge parts being insertable within the other and having an edge substantially parallel to said first-mentioned registering walls and adapted to abut against a rail member secured to the other of said hinge parts when said hinge parts are swung to their limit of pivotal movement in the other direction.

5. In combination, a pair of adjacent aligned post sections, a hinge comprising a pair of parts, one of said parts being made of a single piece of material having a top wall, an end wall of double thickness of material, a pair of side walls connecting said top and end walls to form a channel adapted to receive one end of a rail therein, the other of said hinge parts comprising a one-piece member having an end wall adapted to register with and abut against the lower end of the end wall of the first-mentioned hinge part and provided with a pair of parallel side walls spaced apart to be slidably insertable between the side walls of the first-mentioned hinge part, pivotal connecting means between the side walls of both of said hinge parts and means for connecting each of said hinge parts to a post section.

6. A hinge comprising two cooperating parts arranged for operative attachment to a cooperating apparatus, one of said parts consisting of a plate formed with a flange at either edge, with the end flanges extending and overlapping at the end of the plate, the other of said members consisting of a plate provided with side flanges having their ends extended and brought adjacent, said last-mentioned member inserted between the side flanges of the other member, and means for pivotally securing the side flanges of said members together, said members having a limited pivotal movement whereby the plates may be brought parallel or at an angle to each other.

7. In combination, a pair of post sections adapted to be arranged end to end in alignment, a rail member connected to one of said post sections and adapted to be disposed perpendicularly thereto, a hinge member secured to said post section, and a second hinge member secured to the other post section and pivotally connected with the first mentioned hinge member, said second hinge member having a portion adapted to abut with a portion of said rail member when the post section to which it is secured is swung to a position substantially parallel to the rail member.

In testimony whereof, I have hereunto signed my name.

WILLIAM A. MATHESON.
